FIG. 3.

UNITED STATES PATENT OFFICE.

PETER BURD JAGGER, OF LONDON, ENGLAND.

ROPE-UNTWISTING APPARATUS.

Application filed November 23, 1921. Serial No. 517,387.

To all whom it may concern:

Be it known that I, PETER BURD JAGGER, a subject of the King of Great Britain, residing at London, England, have invented 5 certain new and useful Improvements in and Relating to Rope-Untwisting Apparatus, of which the following is a specification.

This invention relates to improvements in 10 mechanism for mechanically untwisting and reeling or spooling the separate strands of a rope or the separate wires or groups of wires of a strand.

In my prior United States Patent 15 1,448,543 there is set forth mechanism for carrying out the above operation, the mechanism comprising spools or bobbins or drums mounted so as to revolve on a common axis, while simultaneously rotating independently 20 on their own axes, a gripping device for gripping the rope or the like at a point situated on the produced common axis aforesaid, this gripping device revolving on the common axis in the same direction as the spools or bobbins, and at a speed, relatively to the 25 spools or bobbins, to ensure untwisting.

According to the present invention the drive of rotation of each spool or drum round its own axis is effected by independent driving means capable of being operated to reel its appertaining wire or strand at a rate of speed which may be varied independently of a given orbital speed of the spool so as to accommodate any particular rate 30 of delivery from the strand or rope being untwisted.

Independent driving means operating intermittently serve well.

Thus under the present invention the rotatory movement of each spool of a number 40 of spools, or each group of a number of series of spools is controlled and regulated according to conditions in working and independently of a given orbital speed of the 45 spools, this conducting to a more efficient running of the spools or bobbins for "take up" and ensuring an increased efficiency in the general working of the machine; the setting for the reeling of the strand or wire 50 in accordance with any given speed of the machine and hence in proportion to the amount of unwinding taking place at that speed being easy. The rotatory movement of any spool or any series of spools can be cut 55 down or lengthened or stopped without af-

fecting the rotary movement of any other spool or series of spools. Further under the present invention a group selection of certain of the spools may be made for reeling corresponding to the number of separate strands or separate wires, or groups of wires, to be untwisted and reeled in a particular job, the idle spools then simply revolving about the common axis without having a rotatory movement imparted thereto. 60

As a drive for a spool or drum means of the go and return character serves well.

An example of such a drive is constituted by a cam component or its equivalent carried for example on the framework of the 70 machine, and operative, during a period of the revolution of the spool, on a movable slide or link component, to thereby impart to the spool a partial movement of rotation in a direction suited to the reeling thereon of 75 the wire, etc., the slide or link component being under bias to return to normal position as soon as the operative period ends. The coupling between the slide or link component and the spool is so arranged that 80 the return movement of the slide component does not impart a backward movement of the spool.

The gripping rolls on the supply side of 85 the machine may have a partial rotatory movement intermittently imparted thereto in the desired direction in a manner similar to the movement imparted to the spools.

A modified form of drive for the drums is also set out in the following description. 90

The accompanying drawings illustrate a form of machine under the present invention.

Figs. 1 and 2 are respectively side elevation and plan views of the spool side of the 95 machine having a pawl and ratchet wheel drive for the spool and drum. Figs. 3 and 4 are respectively side elevation and part plan of the gripping or supply side of the machine showing a drive for the gripping rolls. Fig. 5 is an elevation of the cam disc and Fig. 6 an enlarged view of the pawl and ratchet wheel drive.

Referring to Figs. 1, 2 and 5 and 6 of the drawings a constructional form of drive under the present invention as applied to the form of machine set out in my prior Patent No. 1,448,543 comprises a cam 1 mounted on a disc or plate 2 attached to the framework of the machine. Each spool or drum 105

3 is mounted on its own spindle 4 in a carrier 5 which is connected to the revolving drum or annulus 6 and revolves therewith. To accommodate the working of the machine to the tension or drag of the rope or the like each carrier 5 is mounted so as to freely rotate about its longitudinal axis. Each spool 2 has a partial rotatory movement intermittently imparted thereto in the desired direction about its spindle 4 by means of a ratchet wheel 7 fixed on the spool and a one-way acting ratchet pawl or click 8 cooperating therewith. Movement is imparted to this pawl by a lever and link feed device 9 slidably carried by the carrier previously referred to. Slots 5^a allow for the back and forth movement of the feed device in the carrier. A non-return detent 10 is provided for the ratchet wheel. The end of the feed device remote from the ratchet pawl or click is so fashioned as by a projecting offset or spindle 11 as to contact with a cam 1 or a number thereof during each revolution about the common axis, and at such contact the ratchet pawl operates the ratchet wheel on the spool, thereby giving a partial rotatory movement to the spool and reeling a portion of the strand or wire on to the spool. The feed device is under spring control 12 for effecting a return to normal position upon breaking contact with the cam.

The cam 1 is arranged adjustable by means of a pivotal mounting and an adjusting screw 13 controlled by a hand wheel 14. Thus the setting of the cam can be effected to regulate the extent of the partial rotation of the spool, or to withdraw the cam entirely from the path of movement of the offset or spindle.

The lay out of the cams is dependent on the positioning of the carriers on the revolving drum. Thus one cam may suffice for a number of spools when these are mounted so as to travel in the same orbital path.

In Figs. 1 and 2 are shown suitable means 16 for distributing the windings on the spool. 17 is a suitable form of confining device and 18 is a suitable form of conducting device for the separate wires or groups of wire of a strand. 17 is driven by 18 through the medium of the bevel wheels 18^a and 17^a. 19, 19^a is the drive for the drum or annulus 6.

Referring to Figs. 4 and 5, the gripping rolls 20 are mounted in adjustable bearings 21. The rolls 20 are under the control of a drive of the reciprocating character whereby the feed of the wire is effected. This drive is indicated by an adjustable cam component 21 and slide or link component 22, 22^a under bias to return to normal position. The slide or link component 22, 22^a has one way acting ratchet pawls or clicks 23 co-

operating with ratchets 24 on the gripping rolls 20. 25 is the supply roll and 26, 27 the drive for this side of the machine.

In the particular machine shown the wire is taken from the supply roll 25 through the hollow driving shaft 27 to the gripping rolls 20. After leaving the gripping rolls each strand is passed to its respective confining device 17, conducting device 18, distributor 16 and spool 3.

The main core is led through the hollow driving shaft 19^a to the end of the machine.

What I claim is:

1. Mechanism of the kind set forth comprising spools mounted so as to revolve about a common axis and means whereby the spools have a rotatory movement on their own axes intermittently imparted thereto, for the purposes described. 80

2. Driving means as claimed in claim 1 hereof of a reciprocating character. 85

3. Driving means as claimed in claim 1 hereof having an operative component for each group of a number of series of spools. 90

4. Driving means as claimed in claim 1 hereof wherein the rotatory movement of a spool can be varied or stopped without affecting the rotatory movement of any other spool. 95

5. Driving means as claimed in claim 1, wherein the rotatory movement of a series of spools can be varied or stopped without affecting the rotatory movement of any other series of spools. 100

6. Mechanism as claimed in claim 1 hereof so arranged that a group selection of certain of the spools may be made for reeling. 105

7. Mechanism of the kind set forth comprising spools, an engaging component on the machine frame, a slide component mounted on the spool carrier and operated on by said engaging component for imparting to said spools a movement of rotation substantially as described. 110

8. In mechanism as claimed in claim 7 hereof a spring control for returning the slide component to normal position at the end of the operative period. 115

9. Mechanism as claimed in claim 7 hereof having a cam as the engaging component. 115

10. Mechanism as claimed in claim 7 hereof having a ratchet wheel on the spool and a one-way acting ratchet co-operating therewith. 120

11. Mechanism of the kind set forth for mechanically untwisting and reeling or spooling the separate strands of a rope or the separate wires or groups of wires of a strand, comprising gripping rolls on the supply side of the machine and means for intermittently imparting rotation thereto. 125

12. Driving means as claimed in claim 11 hereof comprising a slide component, an engaging component operating on said slide component for imparting to gripping rolls 130

on the supply side of the machine a partial movement of rotation.

13. Driving means as claimed in claim 11 hereof wherein the engaging component is 5 arranged adjustable for the purpose described.

14. Mechanism of the kind set forth comprising spools mounted so as to revolve on a common axis, a ratchet wheel on each of 10 said spools, a one-way acting ratchet pawl

co-operating therewith, a lever and link feed device slidably carried by the spool carrier and operating said ratchet pawl and a cam on the framework of the machine for contacting with said lever and link feed 15 device.

In testimony whereof, I affix my signature.

PETER BURD JAGGER.
